UNITED STATES PATENT OFFICE

158,352

BOX INLAID WITH MOTHER-OF-PEARL

Mario J. Ambrosino, River Forest, Ill.

Application June 2, 1949, Serial No. 3,001

Term of patent 3½ years

(Cl. D58—12.6)

To all whom it may concern:

Be it known that I, Mario J. Ambrosino, a citizen of the United States, residing at River Forest, in the county of Cook and State of Illinois, have invented a new, original, and ornamental Design for Box Inlaid with Mother-of-Pearl, of which the following is a specification, reference being had to the accompanying drawings, forming a part thereof.

In the drawings:

Figures 2, 3 and 4 are, respectively, a rear perspective view, a front elevation and a side elevation of the box.

I claim:

The ornamental design for a box inlaid with mother-of-pearl, substantially as shown.

MARIO J. AMBROSINO.
